UNITED STATES PATENT OFFICE.

ALBERT F. DAUM, OF PITTSBURGH, PENNSYLVANIA.

FUSE.

1,222,937.

Specification of Letters Patent.

Patented Apr. 17, 1917.

Application filed May 10, 1913. Serial No. 706,816.

To all whom it may concern:

Be it known that I, ALBERT F. DAUM, a citizen of the United States, residing at Pittsburgh, in the county of Allegheny and State of Pennsylvania, have invented certain new and useful Improvements in Fuses, of which the following is a specification.

My invention relates to improvements in fuses and more particularly to that class of current protective devices known as cartridge or refillable fuses.

Among the objects of my invention are:

1: To provide a simple means for indicating whether the fusible element has been blown.

2: To provide means for connecting together the cap, the clamping bar or washer, the shell, and the fusible element so as to form a unit, the construction preferably permitting relative movement of the shell and the other parts longitudinally of the shell.

3: To loosely connect the clamping element, as a bar, washer, or the like to the shell so as to permit the clamping element to move longitudinally of the shell when in use and so as to keep the shell and clamping element assembled, but readily separable, when the cap is removed.

4: To provide a construction in which the fusible element is maintained under a sufficient tension to cause it to separate or open the circuit before the fusing or melting point of the fuse element is reached and quickly separate at the point where it blows when the element has been weakened at such point, thereby insuring sensitive action where the fuse element is of the well-known structure and type.

5: To construct the parts so that various sorts of terminal attachments may be readily attached and detached without requiring any reconstruction of the elements to which the attachments are applied.

Other and further objects are to provide a structure which is simple and efficient in operation, durable in construction, and which can be manufactured and sold at a relatively low cost, and which can be readily refilled at will.

To these and other ends, the nature of which will be readily understood as the invention is hereinafter disclosed, the said invention consists in the improved construction and combination of parts hereinafter

fully described, illustrated in the accompanying drawings, and more particularly pointed out in the appended claims.

In the accompanying drawings, in which similar reference characters indicate similar parts in each of the views:

Figure 1 is a view partly in section and partly in elevation showing one form of the invention.

Fig. 2 is a fragmentary view showing how the parts are assembled.

Fig. 3 is a detail view illustrating one way in which the fuse element may be positioned relative to the clamping bar prior to the placing of the cap in position.

Fig. 4 is a cross-sectional view of one end of the fuse showing a modified form of my invention.

Fig. 5 is a view of similar character to Fig. 4 showing another form of the invention.

Fig. 6 is also a view of the character of Fig. 4 showing a still further modification.

Fig. 7 is a view partly in elevation and partly in section showing my improved terminal attachment applied to a cartridge fuse.

Fig. 8 is a detail view showing the terminal attachment illustrated in Fig. 7.

Fig. 9 is a modification of the attachment shown in Fig. 8.

Fig. 10 is a detail view of a terminal attachment which may be employed in place of that indicated in Fig. 7, and,

Fig. 11 is a view of similar character of Fig. 4 showing a still further modification.

Referring more particularly to Figs. 1, 2, and 3, the shell is indicated at 15, being preferably formed of any suitable insulating material. 16 indicates the clamping element, in this instance, in the form of a bar, the element having its ends seated against the end of the shell, the bar ends being preferably cut out on the inner side to form shoulders 17 which lie within the end of the shell and serve as stops to limit the longitudinal movement of the bar. The clamping element 16 is preferably in the form of a bar but this is not arbitrary, since it may be in the form of a washer, as indicated at 16^a in Fig. 5, the washer being cut-away or having one or more perforations for the passage of the fuse element to the outer side of the clamping element or washer.

18 designates the cap, preferably of a good conducting material, such for instance, as copper, said cap having its skirt extending over the end of the shell and thus inclosing the ends of the clamping bar 16. 5 The cap may be of any desired form as to terminal structure, and in the form shown in Figs. 4 and 6, the cap is shown as provided with a plurality of openings 18* through 10 which are adapted to pass screws 19 which thread into the clamping element 16, this arrangement serving to provide relative movement between the cap and the clamping element so as to practically unite these into 15 a unitary structure, the fuse element, indicated at 20, extending between the opposing faces of the cap and clamping bar, the action of the screws causing the fuse element to be positively clamped between the bar and cap and held in such clamped relation regardless 20 of any tendency of a relative movement between the cap and the shell, such as may be provided by expansion or contraction of the shell or a blowing of the fuse, the shell and 25 cap, in the forms of my invention disclosed herein, not having a threaded engagement, provision being made as presently explained for a limited relative movement of the cap and shell.

30 In the drawings, I have shown various ways in which this unit is connected to the shell in such manner as to permit of a limited relative movement of cap and shell.

In each instance, I have shown the shell 35 as provided with openings 15*, these openings being spaced from the end of the shell and located preferably at diametrically opposite points, the openings being of a length longitudinally of the shell to provide the 40 functions presently referred to.

Various ways of forming the element cooperating with the openings 15* are shown in the drawings. For instance, in Figs. 1, 2, 3, and 7, I have shown this element as in the 45 form of a bar 21, said bar being connected to the inner side of the clamping bar 16 by a screw 22; in the form shown in Fig. 4, I have shown this element as in the form of prongs 23 formed integral with the clamping bar, each of these forms showing the connecting member as carried by the clamping bar or element. In Fig. 6, I have shown this connecting bar as in the form of a bolt 50 22, which is carried by the skirt of the cap, said bolt extending through the openings 15*.

In Figs. 5 and 11, I have shown the connecting element as carried by the end of the shell, the clamping bar or washer being threaded on to such connecting element.

55 In each of these forms, the portion which enters into the openings 15* is of less thickness than the length of such openings, the result being that there is permitted a movement of the connecting element longitudinally of the shell within the elements pro-

vided by the opposite ends of the openings 15*.

As a result, the unity is practically held from passing off of the end of the shell and yet is capable of a movement longitudinally 70 of the shell a distance equal to the play provided by the openings 15*, thus permitting of the use of shell and caps free from connecting screw threads.

As will be readily understood from the 75 drawings, the fuse element which may be in strip or wire form, is secured between the clamping element and the cap, and as both ends of the fuse are assumed to be of similar construction it will be readily understood 80 that in securing the fuse element in position, the connection is made so as to practically retain the connecting members at the ends of the openings 15*, the fuse element itself acting to retain the units at the opposite ends 85 of the fuse in this position, it being readily understood that any tendency of the end caps or units to move outwardly during normal conditions is resisted by the fuse element. To place the parts in position, it is 90 to be understood that the cap and clamping element are separated by the withdrawal of the screws 19, thus separating these two elements. If the clamping bar is to be placed 95 in position, the operation shown in Fig. 2 is provided by passing one end of the connecting member into one of the openings 15* with the clamping bar in approximately the position shown, and then moving the clamping bar so as to bring the other end of the connecting member into the opposite slot, this 100 operation being possible through the length of the openings or slots and the plate heretofore referred to. This enables the clamping bar to be placed in position. The fuse 105 element is then passed about the clamping bar in such position, as for instance shown in Fig. 3, after which the cap is placed in position and the screws 19 inserted to draw the clamping bar and cap into clamping relation to the fuse element. After one end of the fuse element is secured by this clamping action, a similar operation is provided at the opposite end of the shell, the clamped end of the fuse element permitting sufficient pulling 110 strain to be placed on the element to carry it in proper position around the clamping bar at the opposite end so as to insure the connecting bar at that end being at the inner end of the slots or openings 15*. The well-known type of fuse element is of such a 115 character as will enable the bending action to readily take place and the bends will be sufficient to retain the parts in position until the caps are secured so as to clamp that end 120 of the fuse element.

The fuse element may or may not be placed under tension, as desired. In Fig. 6, the structure is such that the fuse element is not placed under tension; this may or may 130

not be true of the structure of Fig. 4, depending upon whether or not the clamping bar is formed of a resilient or non-resilient metal. In the form shown in Fig. 1, the connecting member 21 is somewhat resilient, so that when the fuse is filled and the end caps in position, the fuse is held under the tension provided by this connecting member, contacting with the inner ends of the slots or openings; obviously this connecting member may not be made of resilient material, in which case, the fuse element is not placed under tension.

The advantage of placing the fuse element under tension, as for instance, indicated in Fig. 1, lies in the fact that when the fuse element blows, the separation will take place at the earliest possible moment and will open the circuit before the melting point of the fuse element is reached, the weakening of the element at the point where it blows permitting the tension exerted by the connecting member to become effective to quickly separate the parts of the fuse element and not necessitating awaiting the actual melting or fusing of the element at this point, this being one of the disadvantages resulting from the use of this type of fuse element in prior constructions. As a result, the element of safety and certainty of operation is provided to a greater degree.

In either form, the blowing of the fuse and the expansion provided within the shell causes either one or both of the units at the ends of the shell to be moved outwardly within the limits of the play provided by the openings 15^a, this movement obviously providing rapid separation of the remaining ends of the fuse element without, permitting the caps or units to actually leave the shell, the connecting members acting to hold the units from passing out of position.

Obviously, with the normal positions of the caps known, such outward movement of the end caps will readily demonstrate the fact that the fuse element has blown and thus provide a fuse which will indicate this fact; where a number of fuses are positioned on the switch board in alinement, the change in position will be readily perceived without examination by a comparison with the position of the end caps, of adjacent fuses. To enable individual inspection, the shell may be provided with a suitable indicating mark indicated at 25 in Fig. 1, which would show the normal position of the cap either by being in approximate alinement with the end of the cap or by being inclosed by the skirt of the cap; in the former case, the blowing of the fuse would cause the cap to move longitudinally of the shell and thus have its inner end spaced from such indicating mark, while in the case of the mark being normally inclosed or covered by the skirt, the blowing would cause the skirt to pass

to a point where the mark would be exposed and thus provide visual indication of the fact that the fuse has blown.

The connecting member shown in Fig. 5 is in the form of a rod-like element bent to provide parts which will enter the slots or openings 15^a.

The form shown in Fig. 11 differs in that the connecting member is preferably formed of resilient metal and doubled upon itself to provide a crossing of the inner end portions, the doubled intermediate portion being preferably threaded to engage shoulders in the cap and the clamping member. In this particular form, the resiliency of the member will cause the ends to be spaced apart a less distance when the member is inserted in position, and the threading of the cap into position acts to press the doubled portions toward each other, this action causing the ends to be moved outwardly so as to be positioned within the slots or openings and thus provide the connection between the shell and the unit formed by the cap clamping member, it being readily understood that while movements of the unit longitudinally of the shell may take place, the cap acts to prevent retraction of the ends of the member and thus prevent disengagement.

As will be readily understood, the units can be taken off or placed in position, thus enabling the fuse to be readily refilled without difficulty.

In connection with the drawings, I have shown various types of terminals which may be employed in connection with the present invention. In Fig. 1, for instance, I have shown the cap as provided with single knife terminals 26.

Fig. 4 is not essentially different from Fig. 1 excepting that it is provided with the U-shaped terminal 27 having its central portion secured against the outer face of the cap by the screws 19 which perform the double function of clamping the fusible element 20 and securing the terminal 27 to the cap. This terminal is a flat strip of conducting metal having its ends bent down so as to lie parallel with the cap or shell. The ends of the terminal are adapted to lie between the blades 28^a of the line terminals 29^a.

In Fig. 7, I have shown the fuse as provided with U-shaped terminals 28 connected thereto, these being more particularly shown in Fig. 8, consisting of a piece of sheet metal having a centrally projecting member 28^a bent up at right angles thereto and two end portions 28^b bent up at a right angle to the central portion, the central portion and the two ends 28^b constituting a U-shape to receive the sides of the cap, the member 28^a resting against the end of the cap to which it is secured by the screw 19. This screw 130

may be the screw which also passes through the cap and the clamping member to clamp the fusible element.

The terminal 29 shown in Fig. 9 has its central member 29^a provided with two holes for the screws 19 so that it may be substituted for the terminal 27 in Fig. 4.

In Fig. 10, I show a different type of terminal which may be used in place of the terminal shown in Fig. 8.

As will be seen, the general structure of the fuse shown herein is adapted to coöperate with many different types of terminals without changing present equipment, a positive advantage in fuse construction.

Obviously, the fuse may be provided with the usual asbestos filling or insulating powder or equivalents thereof, this not being shown as it is a common expedient.

While I have herein shown and described various ways in which my invention can be carried into effect, it will be readily understood that variations and modifications therein may be required or desired to meet the exigencies of use, and I desire to be understood as reserving the right to make any and all such changes and modifications as may be required or desired in so far as the same may fall within the spirit and scope of the invention as expressed in the accompanying claims.

Having thus described my invention, what I claim as new is:

1. In a fuse, a shell, having openings therein, a cap on the end of the shell, a clamping member within the cap, a fusible element clamped between the cap and the clamping member, and means coöoperating with the said openings for permitting the cap to have a limited movement longitudinally of the shell.

2. In a fuse, a shell, a unit composed of a cap on the shell, a clamping member in the cap, and a fusible element clamped between the cap and said member independently of contact with the shell, and means projecting from the unit for permitting a limited movement of the unit longitudinally of the shell.

3. In a fuse, a shell, a fusible element, means for clamping said element in position within the shell, and means coöoperating with the shell for permitting a limited movement of the clamping means as a unit longitudinally of the shell upon "blowing" of the element.

4. In a fuse, a shell, a fuse element, fuse-clamping means for positioning the fuse element within the shell, said means being movable longitudinally of the shell as a unit, and means coöoperating with the shell for limiting the length of movement of the unit, the fuse element acting to normally restrain the movement of the unit in clamping position, said unit movement being permitted by the "blowing" of the fuse element.

5. In a fuse, a shell, a fuse element, a fuse-element clamping unit movable longitudinally of the shell, and means coöoperating with the shell for placing the clamped fuse element under tension while protecting a circuit, said tension means aiding in disrupting the element when the safety limits are reached.

6. In a fuse, a shell, a fuse element, a fuse-element clamping unit movable longitudinally of the shell, and means coöoperating with the shell for placing the unit under pressure opposed to the element when the latter is protecting a circuit, said means aiding in disrupting the element when the safety limit is reached.

7. In a fuse, a shell, a fuse element, a fuse-element clamping unit movable longitudinally of the shell, and means coöoperating with the shell for placing the unit under pressure opposed to the element when the latter is protecting a circuit, said means aiding in disrupting the element when the safety limit is reached, and also acting to limit such longitudinal movement of the unit.

8. In a fuse, a shell having closed slots, a unit composed of a cap on the shell, a clamping member in the cap, a fusible element between the cap and member, a threaded device for drawing the cap and clamping member one toward the other, and means projecting from the threaded device and into the slots for connecting the said unit to the shell.

9. In a fuse, a shell having holes spaced from the end of the shell, a cap thereon, a clamping member therein, a fusible element clamped between the cap and member, and means projecting from said member and into the holes for connecting said member to the shell, said means being insertable internally of the shell concurrently with the positioning of the member.

10. In a fuse, a shell having holes, a cap thereon, a clamping member therein, a fusible element clamped between the cap and member, and means projecting from said member and into the holes for permitting the member and cap to move longitudinally of the shell within predetermined limits.

11. In a fuse, a shell, a cap thereon, a clamping member therein, a fusible element between the cap and member, a contact terminal, and threaded means for connecting the terminal to the cap and for clamping the fusible element between the cap and said member.

12. In a fuse, a shell, a cap thereon, a clamping member therein, a fusible element between the cap and member, a contact terminal, and clamping screws extending through the terminal and cap and into said member.

13. In a fuse, a shell, a cap thereon, an indication on the shell to identify the normal

position of the cap, and means coöperating with the shell for connecting the cap to the shell to permit a limited outward movement of the cap on the shell.

14. In a fuse, a shell, means for clamping a fuse element within the shell in normal line-protecting position, and means coöperating with the shell for permitting restricted movements to said clamping means longitudinally of the shell when the limit of safety is reached.

15. In a fuse, a shell, means for clamping a fuse element within the shell in normal line-protecting position, and means coöperating with the shell for permitting restricted movements to said clamping means longitudinally of the shell when the limit of safety is reached, said movements being in the direction of increasing the normal length 20 of the fuse.

16. In a fuse, a shell having opposed holes spaced from an end thereof, and a fusible-element clamping member carrying means adapted to extend into said holes for supporting said clamping member against withdrawal, said means being insertible internally of the shell concurrently with the positioning of the member.

17. In a refillable fuse, a shell having opposed holes spaced from the end thereof, an end cap, and a member adapted to coöperate with said cap to clamp a fusible-element, said member carrying means insertible into a plurality of said holes solely from the interior of the shell during the member positioning movements, said means supporting the member against withdrawal.

18. In a refillable fuse, a shell having opposed holes spaced from the end thereof, an end cap, and a member adapted to coöperate with said cap to clamp a fusible element, said member carrying means including laterally-extending portions adapted to enter a plurality of said holes solely from the interior of the shell during the member positioning movements, said means supporting the member against withdrawal.

19. In a refillable fuse, a shell having opposed holes spaced from an end thereof, a member external of the shell adapted to overlap said holes, a member adapted to coöperate with said external member in clamping a fusible element in position, said member carrying means insertible within a plurality of said holes solely from the interior of the shell during its member-positioning movements, said external member in its hole-overlapping position serving to prevent movement of the means within the holes sufficient to permit withdrawal of the means.

20. In a fuse, a shell, a cap on the end of the shell, a clamping member within the cap, a fusible element clamped between the

clamping member and the end of the cap, and means coöperating with the shell for 65 permitting the cap to have a limited movement longitudinally of the shell.

21. In a fuse, a shell having openings, a cap thereon, a clamping member therein, a fusible element clamped between the cap and 70 member, and means within the shell projecting from said member and into the openings for connecting said member to the shell.

22. In a fuse, a shell, a cap thereon, a clamping member therein, a fusible element 75 between the cap and member, a contact terminal, and threaded means for connecting the terminal, cap and member into a unitary structure.

23. In a fuse, a shell, a cap thereon, an 80 indication on the shell to identify the normal position of the cap, and means for loosely connecting the cap to the shell to permit a free limited outward movement of the cap on the shell.

24. In a fuse, a unit comprising a shell having openings, a cap on the shell, a clamping member in the shell, a fusible element between the cap and member, means for forcing the cap and the clamping member 90 one toward the other, and unit-retaining means within the shell and projecting from the unit and into the openings.

25. In a fuse, a unit comprising a shell having openings, a cap on the shell, a clamping member in the shell, a fusible element between the cap and member, means for forcing the cap and the clamping member one toward the other, and lateral projections within the shell and connected to the unit, the 100 projections and openings being arranged to permit one projection to be first slid into one opening, and the other projection, after it has been swung into line with the other opening, to be then slid into the same.

26. In a fuse, a shell, a cap on the end of the shell, a clamping member within the cap, a fusible element clamped between the clamping member and the end of the cap, and means for permitting the cap to have 110 a limited movement longitudinally of the shell.

27. In a fuse, a shell, a unit composed of a cap on the shell, a clamping member in the cap, and a fusible element clamped between the cap and the said member independently of contact with the shell, and means for permitting the unit to have a limited movement longitudinally of the shell.

In testimony whereof I affix my signature 120 in presence of two witnesses.

ALBERT F. DAUM.
